Attorney

UNITED STATES PATENT OFFICE

WILLIAM B. WANSOR, OF LOCUST VALLEY, NEW YORK

BRUSH

Application filed July 18, 1931. Serial No. 551,753.

The present invention relates to that type of brush, broom or mop, in which a worn head may be readily detached from the handle and a new head substituted therefor, an object of 5 the present invention being to provide an exceedingly simple and inexpensive means for attaching the handle to the head, which will securely hold the head against accidental detachment to permit its ready removal when 10 occasion requires.

More particularly the present invention represents an improvement in brooms and brushes of the type exemplified in my prior Patent No. 1,398,052 of November 22, 1921, 15 and a similar Patent No. 1,477,468 of December 11, 1923.

A further object of the invention is to provide a novel construction whereby excess spreading of the fibers of the brush head will 20 be prevented while unnecessary weight is avoided.

Still another object resides in the provision of structure well adapted to paint brushes wherein paint picked up by the fibers will be 25 prevented from reaching the head holder and also from reaching the handle.

To the attainment of the foregoing and other objects which will appear as the description proceeds, reference may be had to the accompanying drawing in which:—

Figure 1 represents a perspective of the assembled brush.

Figure 2 is a side elevation, partly in section, showing the brush head attached to the 35 handle.

Figure 3 is an end elevation partly in section showing the brush head mounted in the handle, and

Figure 4 is a detailed perspective illustrating the holder by means of which the brush head is connected to the handle.

Referring more specifically to the drawing, in which like reference numerals represent like parts, it will be observed that this invention comprises a brush head 10 formed of fibers, bristles or straws 11, suitably bound and secured together by any conventional means as, for example, stitching 12.

A holder 13 formed of suitable material, 50 such as sheet metal, bent approximately in

half and conforming generally at its sides to the shape of the brush head is provided on its interior faces with spikes or studs 14. The material from which the holder 13 is made is preferably resilient, so that the sides or jaws 55 or the holder will be hinged or resiliently connected at the bend. Projecting outwardly from the top or bend of the holder are a pair of upstanding resilient prongs 15, these prongs terminating in beveled shoulders 16. 60 The hollow handle 17 for the device, in the present embodiment illustrated as a paint brush handle, is provided with a bell-shaped socket or thimble 18 having an outwardly flared edge 19. 65

In assembling the entire structure, the holder 13 is placed over the brush head 10, the spikes 14 penetrating the fibers. The assembled holder and brush head are then positioned in the bell portion 18 which acts as 70 a cam to force the jaws more securely into engagement with the brush, the projections 15 extending into the hollow handle 17. This handle is provided with transverse openings 20, the lower edges of which function as 75 shoulders or abutments, and when the holder is fully inserted within the bell 18, the shoulders 16 of the projections will snap into the holes 20 in an obvious manner, engaging the aforesaid lower edges thereof and thus 80 securely hold the entire device against removal. The device is then ready for use and in the event that same is used as a paint brush the bell 19 will prevent any paint from flowing onto the handle, regardless of the 85 position of the brush. This outward flare 19 may be omitted, but is desirable in that it facilitates insertion of the holder 13 into the thimble 18, it being understood that prior to such insertion the sides or jaws of the holder are resiliently separated and will be cammed by the flared portion 19, and the sides of the socket 18 into tight fitting engagement with the brush head 10. The tight internal engagement between the bell 18 and the holder 90 13 will act to prevent seepage of paint or other fluid into the handle and, of course, none can travel along the bristles because of the bend of the holder 13, which acts as a 95 closure for the hollow handle 17. 100

When it is desired to replace or renew the brush head 10, an inward pressure on the shoulders 16 will permit ready withdrawal of the entire holder from the handle. As a 5 convenient means of applying initial pressure, the ring 21 may be furnished; the downward movement thereof effecting an inward movement of the bevelled shoulders 16. The pin 22 will prevent loss of the ring.

10 This initial pressure and the initial movement effected thereby is particularly advantageous in the event that the shoulders 15 rust or become "paint stuck" to the bell 18. Removal of the brush head is obviously 15 facilitated by use of the ring 21, although such ring is not an essential part of the invention.

While the present embodiment of the invention discloses a flat sided paint brush and holder, it is obvious that the invention 20 may be readily adapted to many other forms such as brooms, round paint brushes, mops, and the like. In the event that the socket or 25 thimble 18 is of circular cross section rather than elliptical or oval, as in the present form, it will be evident that the shoulder projections 15 will be effective to prevent turning of the brush head and holder in the socket 30 of the handle.

Having thus described my invention what 30 I claim as new and desire to secure by Letters Patent of the United States is:—

1. The combination of a handle, a thimble 35 at the end of the handle, a brush head, a clamp consisting of flared jaws conforming to and engaging against the opposite sides of the brush head, and a resilient bridge connecting said jaws and yieldable prongs connected to said bridge and housed within the handle to normally retain the clamp in 40 position in the handle, said clamp having means to engage the brush head when in position in the handle to rigidly hold said head against movement relative to the handle.

2. The combination of a handle, a thimble 45 at the end of the handle, a brush head, a clamp adapted for insertion in said thimble and consisting of flared jaws conforming to and engaging against the opposite sides of the brush head, said thimble being effective 50 by its engagement with the clamp, to cam the flared jaws into engagement with the brush head; a resilient bridge connecting said jaws and yieldable prongs connected to said bridge and housed within the handle to normally retain the clamp in position in 55 the handle, said clamp having means to engage the brush head when in position in the handle to rigidly hold said head against movement relative to the handle.

60 3. A handle for paint brushes and the like comprising a tubular member, a socket portion connected thereto and having outwardly flared edges, a resilient clamping member and a brush head, said holder being engageable with said brush head, and said flared

portion being effective to cam the sides of the holder into tight fitting engagement with said brush head thereby to secure same in the holder, means projecting from said holder engageable with said socket and said tubular portion effective to retain said holder and brush head in position in the handle and to prevent same from twisting therein. 70

4. A brush comprising a hollow handle, a socket on one end, a holder engageable with said socket and a brush engageable with said holder, means to cam said holder into engagement with said brush thereby to secure the brush into position, means to retain said holder releasably positioned in said socket 80 comprising a projection extending from said holder, an opening in said handle and a shoulder on said projection extendable through said opening, and means to positively move said projection inwardly of said opening.

In testimony whereof I affix my signature.
WILLIAM B. WANSOR.
